UNITED STATES PATENT OFFICE.

CHARLES FREITAG, OF BROOKLYN, NEW YORK.

RAZOR.

SPECIFICATION forming part of Letters Patent No. 707,223, dated August 19, 1902.

Application filed January 11, 1902. Serial No. 89,263. (No model.)

To all whom it may concern:

Be it known that I, CHARLES FREITAG, a citizen of the United States, residing at 24 Cornelia street, borough of Brooklyn, in the county of Kings and State of New York, have invented certain new and useful Improvements in Razors, of which the following is a specification, reference being had therein to the accompanying drawings.

10 This invention relates to razors for shaving; and it consists in applying to the back of the blade a removable gage designed to bear upon and present the cutting edge of the blade at the proper angle to the surface 15 operated upon for effective operation and made capable of removal from the blade when it is desired to sharpen its cutting edge.

In the accompanying drawings I have shown a razor of the usual size and a preferred form 20 of gage which embodies my invention, consisting of a tube of sheet metal of about the diameter shown, which is proportionate to the size of the razor, applied to the back of the blade.

25 Figure 1 of the drawings represents a razor of usual full size with open blade and the gage applied, the view also showing the blade closed in dotted lines. Fig. 2 is an end view. Fig. 3 is a side view of the gage removed;

30 Fig. 4, a view of the entering end of the gage; and Fig. 5, an enlarged cross-sectional view on the line 5 5 of Fig. 1, showing clearly the inturned free edges of the gage and the bearing position of the gage and cutting edge of 35 the blade when applied for use.

The gage 1 is slotted at one side its entire length, as shown in Fig. 3, to allow it to be slid upon and embrace the back of the blade and is held thereon by the resiliency due to 40 its cross-sectional shape. The free edges bordering the slot in the gage are doubled inwardly, as shown at 2 2, Fig. 5, and formed to present an increased frictional bearing-surface upon the blade to hold it firmly, this 45 construction also serving to stiffen the free edges of the gage and preserve its shape.

The outer end of the gage may also be closed by a cap or by flanges 3 3 to form a stop-bearing against the end of the blade, as shown 50 in Fig. 2.

The principal advantage attending the use of the invention is to maintain the cutting edge of the blade at the proper angle by permitting the gage to rest upon the surface operated upon, the blade being thereby held in 55 the proper position to act efficiently and reduce the danger of cutting or abrading the skin.

In the operation of "honing," the blade is required to be held at a more obtuse angle, 60 and for this reason the gage cannot be made integral with the blade. Therefore in this operation the gage is removed, so that the blade may rest flatly upon the hone at the normal angle provided in its construction. 65

The gage is adapted to be applied to and used with all designs of blades and may be made and sold separately as a commercial article.

I am aware that a removable cylindrical 70 clasp adapted to the back of a razor-blade and having rounded corners bearing upon the blade is not new, and I do not, therefore, claim such construction.

In the practice of the invention for shaving 75 purposes the cylindrical form of the gage in cross-section is desirable, but requires a greater frictional bearing-surface of the blade than hitherto devised to prevent the gage from rolling transversely on the blade. Therefore, 80

Having thus fully described my invention, what I claim, and desire to secure by Letters Patent, is—

A removable gage for razor-blades, consisting of a hollow thin sheet-metal cylinder slotted longitudinally for the reception of the back of the blade, the free edges of the cylinder being folded to present an increased frictional bearing-surface upon the blade, to hold the gage firmly in place and prevent the cylindrical body from rocking on the blade, as set forth.

In testimony whereof I affix my signature in presence of two witnesses.

CHARLES FREITAG.
